UNITED STATES PATENT OFFICE.

JAMES BICKNELL CASTLE, OF HONOLULU, TERRITORY OF HAWAII.

CRATE.

1,189,539.

Specification of Letters Patent.

Patented July 4, 1916.

Application filed August 26, 1914. Serial No. 858,581.

To all whom it may concern:

Be it known that I, JAMES BICKNELL CASTLE, a citizen of the United States, residing at Honolulu, in the county of Honolulu, Territory of Hawaii, have invented certain new and useful Improvements in Crates; and I do hereby declare the following to be a full, clear, and exact description of the invention, such as will enable others skilled in the art to which it appertains to make and use the same.

This invention relates to improvements in crates, and has in view crates particularly adapted for use in handling fruit, such as for conveying pineapples from the field to the cannery, as well as for other purposes.

The object of the invention is to provide an improved crate of this character, which may be shipped knocked-down from the manufacturer to the user at a minimum cost for transportation, and which may be readily erected, and embody sufficient strength to withstand the rough handling to which such crates are subjected.

The invention contemplates, a crate having side walls, corner posts secured to the ends of the side walls, stiffening strips or bars of the same length and width respectively as the crate and having their ends terminally overlapping the upper and lower ends of the corner posts; four rod bolts for clamping the crate firmly together, said bolts passing through these overlapping ends and through a groove in each corner post, and end walls and a bottom secured within this structure, as will hereinafter more fully appear.

The invention consists in the novel construction and combination of parts as hereinafter described and claimed, reference being had to the accompanying drawings, forming a part of this specification, in which similar characters of reference indicate corresponding parts in all the views.

Figure 1 is a perspective view of an erected crate embodying my invention. Fig. 2 is a cross-section through one of the corner posts showing the groove for the bolt. Fig. 3 is a perspective view of a crate showing a modification. Fig. 4 is a cross-section through one of the corner posts of the modification shown in Fig. 3. Fig. 5 is an isometric view of a modification of the crate shown in Fig. 3 showing a closed construction.

Referring to the drawings, 6 represents the longitudinal slats of the two sides A,

which are of the full length of the crate with their ends secured to the corner posts 7. The inner face of each corner post 7 is provided its full length with a groove 7^a. Rectangular shaped stiffening strips or bars 8 and 9 of the full length of the crate are provided above and below the two sides A respectively. Similar shorter strips or bars 10 and 11 of the full width of the crate are provided above and below the ends B respectively. The ends of the bars 8 and 9 overlap the ends of the bars 10 and 11 respectively. The bars 10 and 9 terminally overlap the upper and lower ends of the corner posts 7 respectively.

The rod bolts 12 pass vertically downward through the overlapping ends of the bars 8 and 10, the groove 7^a in the corner posts 7, and through the overlapping ends of the bars 9 and 11, successively, as shown in Fig. 1. Previous to clamping together these bars and sides A by the bolts 12, however, the bottom C and the two ends B are placed in position.

The bottom C is formed by the longitudinal slats 13, each slightly shorter than the length of the crate, secured to the cleats 14. The ends of the slats 13 overlap the bars 11, and the cleats 14 are so placed as to be adjacent to the bars 11 and prevent a movement of the bottom C longitudinally. The bottom C is of substantially the same width as the distance between the bars 9 so that the latter prevent a movement of the bottom transversely.

The ends B are formed of the slats 15, slightly shorter than the distance between the sides A, secured to the vertical cleats 16, as shown. These cleats are held between the bars 10 and 11. The cleats 16 abut the corner posts 7, which prevents a movement of the ends B sidewise. The ends of the slats 13 of the bottom C abut the lower ends of the cleats 16, and a nail or pin 18 is passed through the bars 10 into the upper ends of the cleats 16, so that a movement inward of the ends B is prevented. As the ends of the slats 15 cannot pass the corner posts 7 a movement of the ends B outward is also prevented.

In the modification shown in Figs. 3 and 4, the ends of slats 15 of the ends B fit into the groove 7^a in the corner posts 7, but in other respects the construction is the same as above described.

In the modification shown in Fig. 5

crate is of a closed construction. The slats 6 secured to the corner posts 7 form closed sides A. The corner posts 7 are provided with grooves 7^a and 7^b in two adjacent faces, 5 as shown in Fig. 4. The longitudinal stiffening bars 8 and 9 and the transverse stiffening bars 10 and 11 are the same as previously described but are arranged overlapping in an inverted position from that 10 shown in Figs. 1 and 3. The slats 13 of the bottom are placed closely together, secured to the longitudinal cleats 14. The ends of the slats 13 rest on the bars 8. The slats 15 of the ends B engage the grooves 7^b in the 15 corner posts 7, and the bolts 12 clamp the crate together as previously described.

The cover D is composed of the longitudinal slats 17, secured to the battens or cleats 19, the ends of which overlap the bars 9, as 20 shown. One of the cleats 19 near one end of the crate may be removably secured to the slats 17 by the bolts 20, so that by removal of this 25 cleat the cover D may be slid outward under the bar 11 at that end of the crate until the other ends of the slats 17 clear the bar 11 at the opposite end of the crate, whereupon the cover D may be removed without loosening the bolts 12.

I claim:

30 1. A crate comprising side walls, corner posts secured to the ends of the side walls at the inner side thereof, stiffening bars terminally overlapping the ends of the corner posts, rod bolts passing through said over-

lapping ends of the stiffening bars, each corner post having a groove in one of its two inner faces to receive the bolt, and end walls and a bottom held within the structure so formed.

2. A crate comprising, side walls, corner posts secured to the side walls, each corner post having a groove in each of two face stiffening bars terminally overlapping the ends of the corner posts, a bolt in one of the grooves in each corner post adapted to clamp the overlapping ends of said bars to the corner post, a bottom, ends engaging the other grooves in the corner posts, and a cover, substantially as described.

3. In a crate, corner posts each provided with grooves the full length of two adjacent faces, slats having their ends secured to the third faces of said corner posts, stiffening bars with their ends overlapping the ends of the corner posts, bolts passing through the grooves in each corner post through the overlapping ends of said bars and end walls composed of slats attached to cleats, the ends of said slats adapted to engage the other grooves in the corner posts substantially as and for the purpose described.

In testimony whereof I affix my signature in presence of two witnesses.

JAMES BICKNELL CASTLE
